United States Patent Office

Des. 184,673
Patented Mar. 24, 1959

184,673

MILK CARTON HOLDER

James W. Frasure, Sandusky, Ohio, assignor to Evlo
Plastics, Inc., a corporation of Ohio

Application August 6, 1958, Serial No. 52,067

Term of patent 14 years

(Cl. D58—26)

Fig. 3

Fig. 3 is an end elevational view thereof.

The side not shown is the same as the side shown.

I claim:

The ornamental design for a milk carton holder, as shown and described.
